(57) **CLAIM**

The ornamental design for a vertical collapsible container, as
shown and described.

DESCRIPTION

FIG. 1 is a front elevation view of a vertical collapsible
container showing our new design;

FIG. 2 is a right side elevation view thereof, the left side
being a mirror image thereof;

FIG. 3 is a rear elevational view thereof;

FIG. 4 is a top plan view thereof; and,

FIG. 5 is a bottom view thereof.
